PAPER TABLE NAPKIN OR SIMILAR ARTICLE

Bradley Rutledge, Piedmont, and Adam J. Kirth, Alameda, Calif., assignors to Crown Zellerbach Corporation, San Francisco, Calif., a corporation of Nevada

Application February 4, 1958, Serial No. 49,493

Term of patent 14 years

(Cl. D59—2)

The figure is a face view of a quarter section of a paper table napkin embodying our new design, which design is repeated symmetrically on each of the other three quarters of the napkin.

We claim:

The ornamental design for a paper table napkin or similar article, substantially as shown and described.
